UNITED STATES PATENT OFFICE.

EDMOND. MOLLOY, OF PHILADELPHIA, PENNSYLVANIA.

HOT-AIR-DISTRIBUTING FURNACE.

SPECIFICATION forming part of Letters Patent No. 416,734, dated December 10, 1889.

Application filed May 7, 1889. Serial No. 309,392. (No model.)

To all whom it may concern:

Be it known that I, EDMOND MOLLOY, a subject of the Queen of Great Britain, residing in the city of Philadelphia, in the State of Pennsylvania, have invented certain new and useful Improvements in Hot-Air-Distributing Furnaces, of which the following is a full, clear, and exact description, reference being had to the accompanying drawings, forming 10 a part of this specification.

My invention relates to apparatus which may be classified under the title of "hot-air furnaces," and has for its object the distribution of hot and cold air forced under pressure through the usual registers in buildings; and it consists, primarily, of a furnace frame or structure containing, as is usual, a fire-surface and escape-flues, and, in addition thereto, a steam-boiler located over the fire-surface, a separate air chamber or reservoir communicating through apertures with pipes leading to the registers in the building and communicating, also, with a coil of pipe located within the furnace, between the combustion-chamber and the draft-passage thereof, and terminating in a tube or tubes projecting through the side of the furnace structure; secondly, the combination therewith of tubes connected with the induction end of the coiled pipe, the other 25 end of said tubes terminating in one or more rotary fans provided with air-induction tubes, and steam mechanism for operating the said fans, and, finally, in the details of the structure and the combination and arrangement of its 30 several parts.

Referring to the drawings forming a part of this specification, in which like letters of reference refer to similar parts in the several views, Figure 1 is a side elevation showing the 40 general arrangement of the several parts, more particularly the driving mechanism, the fresh-air induction-tube, the rotary fan, the tube connecting it with the coil of pipe within the furnace, the exit-pipe from the hot-air chamber, and the furnace-frame. Fig. 2 is a top view of the parts shown in Fig. 1. Fig. 3 is a vertical section on the line *b b* of Fig. 4 of the furnace structure and its contained parts, showing the arrangement therein of 45 the steam-boiler, the coil of air-pipe, and the air chamber or reservoir; and Fig. 4 is a ver-

tical longitudinal section on the line *a a* of Fig. 3, showing the like parts.

The design of my invention is to draw fresh air from the outside of a building, force it 55 through the apparatus, heating it thereby in winter and cooling it in summer, and deliver it under a moderate pressure to the several registers in the building. The furnace-frame A is constructed, in the usual manner, with a 60 grate G and an escape-flue E, but is so arranged internally that a horizontal or other boiler B may be located therein above the flame-surface, and at the top of the furnace structure is arranged an air-chamber D, forming the top of the furnace, with its under side 65 constituting the top of the combustion-chamber of the furnace and receiving heat therefrom. In the space between the boiler and air-chamber D is arranged one or more coils 70 of pipe F F, with the induction end F' extending through the side of the furnace structure and the ejection end F² communicating with the base of the air-chamber D. The top surface of the air-chamber D is provided with 75 a series of outlet-openings F³, to which are connected the usual pipes from hot-air furnaces leading to the usual discharge-registers in the building. Communicating with the induction-passage F' of the coil of air-heating pipe is a pipe or pair of pipes G G, 80 communicating at the other end with the discharge-opening of a revolving fan-blower H, which may be constructed in any well-known manner. In the drawings is shown a pair of 85 such revolving fan-blowers slightly separated from each other and mounted on a spindle which drives the fans, the spindle N being provided with a pulley-gearing n m, driven by an engine (shown in the drawings as a 90 steam-engine) taking steam through the pipe L from the boiler B in the furnace. It is obvious, however, that the boiler B may be omitted and the requisite power obtained by means of some other form of engine in which 95 steam is not required; or any other motive power may be used to drive the fans in the manner indicated. Connected with the inlet-openings of the revolving fan-blowers are pipes K, which I prefer to lead to the exterior of the building, where a supply of pure 100 fresh air can be obtained. It is obvious that

the arrangement of the blowers and its tubes relatively to the furnace and its contained elements may vary from that shown in the drawings without departing from the principle of the invention.

The operation is as follows: The fan-blowers will produce an inward current of air constantly and force it through the pipes G into the coil of pipe F, located in the furnace-chamber, where it will be heated in its passage through the same to the air chamber or reservoir D, the under side of which also receives heat from the combustion-chamber of the furnace, from whence it will be discharged under a moderate pressure through the eduction-passages F³ into the flues leading to the several registers in the building. If steam machinery is used as a motive power for the fans, it will be seen that the same fire that heats the air delivered to the building will create steam in the boiler to drive the engine M, and that a constant-moving current of air is at all times kept up through the apparatus. My improvement is equally applicable for hot-weather purposes. By a substitution of other steam-supply than from the boiler B, or of a different character of motive power not requiring steam, and the air-chamber B converted from a heating-chamber to a cooling-chamber, not only by the absence of fire in the furnace, but by the adaptability of the chamber D as a storage-reservoir for ice, the current of fresh air pumped into the same by means of the fan-blowers will be discharged through the eduction-passages F³ and through the registers of the building as a current of cool air.

Having thus described my invention, what I claim as new, and desire to secure by Letters Patent, is—

1. A hot-air-distributing furnace consisting of the furnace structure provided with an air-chamber, forming the top of the combustion-chamber, with its under side exposed to the heat thereof, and provided with an eduction-passage, and a coiled pipe within the combustion-chamber communicating at one end with said air-chamber and at its other end with the open air without the furnace, substantially as described.

2. A hot-air-distributing furnace consisting of a furnace structure provided with an air-chamber, forming the top of the combustion-chamber, with its under side exposed to the heat thereof and provided with an eduction pipe or pipes, and a series of independent coiled pipes within the combustion-chamber, each communicating at one end with said air-chamber and at its other end with the open air outside of the furnace, substantially as described.

3. A hot-air-distributing furnace consisting of a furnace structure provided with an air-chamber, forming the top of the combustion-chamber, with its under side exposed to the heat thereof and provided with an eduction-pipe, a coiled pipe within the combustion-chamber communicating at one end with the said air-chamber and at the other end with the air outside of the furnace, and a fan for supplying air to said pipe, substantially as described.

In testimony whereof I have hereunto affixed my signature this 27th day of April, A. D. 1889.

EDMOND MOLLOY.
